UNITED STATES PATENT OFFICE.

WILLIAM B. SHEDD, OF EAST BOSTON, MASSACHUSETTS.

IMPROVED HAT-BRUSH.

Specification forming part of Letters Patent No. 36,239, dated August 19, 1862.

To all whom it may concern:

Be it known that I, WILLIAM B. SHEDD, of East Boston, in the county of Suffolk and State of Massachusetts, have invented a new and useful Improvement in Hat-Brushes; and I do hereby declare that the following is a full, clear, and exact description of the same, reference being had to the accompanying drawings, forming part of this specification, in which—

Figure 1 is a back view of a hat-brush with my improvement. Fig. 2 exhibits a vertical section of a hat and a side view of the brush, showing the manner in which the latter is to be applied to be carried within the former.

Similar letters of reference indicate corresponding parts in both figures.

The object of this invention is to enable a hat-brush to be carried in the hat without inconvenience; and to this end it consists in providing the brush with a spring-clasp suitably arranged on its back and near one end to attach it to the sweat or head lining of the hat.

The brush itself may be of any construction; but I prefer to make it of a thin flat piece of wood, A, covered on its face with plush, a, as it is an object to have it as thin as possible, and in such case I attach to the back a handle, B, to enable it to be easily laid hold of and used. C is the clasp, composed of a piece of sheet-brass or other metal, having attached to it a thumb-piece, d, of wire, or made all of

one piece and attached to the back of A by a coiled spring, b, which operates like a hinge, and also acts to press the end c of the plate toward the back of A, but yields to pressure of the thumb applied to the thumb-piece for the purpose of removing the end c from the back of A.

When the brush is placed in the hat, the thumb-piece is pressed upon to remove the end c of the clasp from the back of A, and the end of the brush next to which the thumb-piece is attached is slipped between the sweat f and the body of the hat, with the face of the brush next the hat-body, and the clasp is brought over the sweat. The opposite end of the brush is then pressed against the crown of the hat, and on the clasp being released the spring b presses it against the sweat, to which the brush is thus secured. I prefer to apply the brush at the back of the hat, as in that position it will not inconvenience the wearer.

What I claim as my invention, and desire to secure by Letters Patent, is—

Furnishing the brush with a spring-clasp, applied and arranged upon its back to operate substantially as and for the purpose herein specified.

W.M. B. SHEDD.
